FABRIC SUPPORT FOR IRONING BOARDS

Florence Irene Detwiler, Cleveland, Ohio

Application October 26, 1949, Serial No. 123,683

2 Claims. (Cl. 38—111)

1

The invention relates to attachments for ironing boards, and particularly to devices of this character adapted to hold off the floor depending parts of the article being ironed.

The objects of the invention are to provide an article of the character stated which may be readily and conveniently attached to and removed from the ironing board, which performs its function without inconvenience to the ironer, which is adaptable to different types and sizes of ironing boards, which is sturdy, and which, when not in use, can be readily folded and gathered into a relatively small package for convenient storage.

The annexed drawings and the following description set forth in detail certain means illustrating the improvements in attachments for ironing boards, the same, however, showing only one of the various forms in which the principle of the invention may be embodied.

In said annexed drawings:

Figure 1 is a side elevation of one standard type of ironing board to which the improved attachment is applied in operating position;

Figure 2 is a top plan of the ironing board and the attachment shown in Figure 1;

Figure 3 is a front elevation of the assembly shown in Figure 1;

Figure 4 is a fragmentary bottom plan of the wire supporting and strengthening skeleton member, and the fabric material of the attachment associated therewith, in partially assembled condition;

Figure 5 is a complete bottom plan of the strengthening skeleton element shown in Figure 4, in completely assembled condition;

Figure 6 is a vertical section, upon an enlarged scale, taken in the plane indicated by the line 6—6, Figure 5; and

Figure 7 is a vertical section, upon an enlarged scale, taken in the plane indicated by the line 7—7, Figure 5.

Referring to the annexed drawings in which the same elements are indicated by the same respective numbers in the several views, a standard type of ironing board is shown having a top board 1, a pair of rear corner legs 2 pivotally secured to the under surface of the board 1, a central leg 3 also pivotally secured to the bottom surface of the top 1 intermediate the width of the latter, and wire braces 4 which are pivotally mounted in and connect the legs 2 and 3, all as well understood in the art. By virtue of the aforescribed assembly, the ironing board can be assembled for functioning into the structure

2

clearly shown in Figure 1, and can be folded into a substantially flat assembly for storage when not being used.

The improved attachment comprises a fabric member 5 and two wire parts 6 and 7 jointed together to form a skeleton strengthening and stretching frame.

The attachment is suspended from the bottom surface of the ironing top board 1 adjacent the front and rear of the latter by means of a front chain 8 and a pair of rear chains 13. The front chain 8 is fastened at its two ends to eyelets 9 welded or otherwise suitably secured to the respective wire frame parts 6 and 7, and passes through an end eyelet part of a hook 10 engaging an eyelet screw 11 fastened to and depending from the bottom portion of the top 1.

Depending from two corner eyelet screws 15 secured to the under surface of the board 1 at the rear of the latter, and upon opposed sides thereof, are two hooks 14 from which the pair of chains 13 respectively depend and engage at their lower ends a pair of rings 12 welded or otherwise suitably secured to the respective rear end portions of the wire frame parts 6 and 7. Thus, the wire frames 6 and 7 are suspended front and rear from the bottom of the board 1 by means of the chains 8 and 13, as clearly shown in Figures 1 and 3.

The fabric material element 5 is a single piece of cloth having a large clearance area 19 at one end, thus serving for passage therethrough of the wire braces 4, and a large opening 20 formed at a substantial distance from the opposite end of the fabric 5 and serving for passage therethrough of the ironing board leg 3. Also, the fabric material 5 is cut, as indicated by number 21, Figure 2, between the adjacent ends of the openings 19 and 20. The wire frame parts 6 and 7 are housed in hems 17 formed in the free edges of the fabric material 5 and removably retained therein by a multiplicity of snap fasteners 18. The adjacent wire frame portions at the inner edges of the wire parts 6 and 7 are not housed in hems with the exception of the wire parts bounding the cut 21.

The wire frame parts 6 and 7 are removably fastened together along the line of the fabric cut 21 by a fastening element 22, Figure 7, which is welded to the wire frame part 6 and has a hook end member 23 which is passed through the adjacent portion of the hem 17 and removably engages the wire frame part 7. The wire frame parts forwardly of the opening 20 are fastened together by a hinge 26, Figure 6, having two

leaves 24 and 25 respectively welded or otherwise suitably secured to the respective frame portions 6¹ and 7¹ and pivotally connected by a hinge pin 27.

It is evident from the foregoing description, and particularly upon reference to Figure 5 of the drawings, that the two wire frame parts 6 and 7, when not being used, can be folded flat in opposed relation with the fabric material 5. Also, that when it is desired to remove the fabric piece 5 from the wire frame parts 6 and 7, for laundering or other purposes, it is necessary only to unfasten the hook 23 from the wire part 7, and unsnap the fasteners 18.

What I claim is:

1. An attachment for ironing boards comprising a substantially flat fabric body formed with openings for the passage therethrough of supporting structure of an ironing board, said body having a peripheral hem, a substantially flat strengthening wire frame comprising two similar skeleton side parts each having an outer portion detachably secured in the body hem and an inner exposed portion, the inner wire portions lying closely adjacent to each other but being flared outwardly to match the fabric body openings, the two side parts of the frame being hinged together at their inner portions for folding of

the frame and fabric body into a compact package, and means secured to the frame parts for detachably suspending the attachment from an ironing board.

2. An attachment for ironing boards, characterized as in claim 1, in which the fabric body has a detachably fastened hem portion on one side of a supporting structure opening, said hem portion receiving adjacent sections of the inner wire portions, in which a hook is secured to one inner wire portion and is passed through the said detachably fastened hem portion and detachably engages the adjacent wire portion, and in which a hinge connects the two inner wire portions on the opposite side of said supporting structure opening.
